[57] CLAIM

The ornamental design for a combined hand-held portable vacuum cleaner and brush attachment, as shown.

DESCRIPTION

FIG. 1 is a reduced perspective view of a combined hand-held portable vacuum cleaner and brush attachment, showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and

FIG. 7 is a rear elevational view thereof.
